Primary Examiner — W. A. Teddy Falloway

(57) **CLAIM**

The ornamental design for a dishware with utensil-holding features, as shown and described.

DESCRIPTION

FIG. 1 is a top-front-left perspective view of a dishware with utensil-holding features showing my new design;
FIG. 2 is a top-front-right perspective view thereof;
FIG. 3 is a bottom-rear-left perspective view thereof;
FIG. 4 is a bottom-rear-right perspective view thereof;
FIG. 5 is a front elevational view thereof;
FIG. 6 is a rear elevational view thereof;
FIG. 7 is a top plan view thereof;
FIG. 8 is a bottom plan view thereof;
FIG. 9 is a right elevational view thereof;
FIG. 10 is a left elevational view thereof;
FIG. 11 is a top-front-left perspective view thereof, wherein a utensil is shown held by a utensil-holding feature of the dishware;
FIG. 12 is a top-rear-left perspective view thereof;
FIG. 13 is a top-front-right perspective view thereof, wherein a utensil is shown held by another utensil-holding feature of the dishware; and,
FIG. 14 is a top-rear-left perspective view thereof.
The broken lines showing a dishware brim in FIG. 1-14, the broken lines showing a bottom surface in FIGS. 3, 4, and 8, and the broken lines showing a utensil in FIG. 11-14 are included for the purpose of illustrating environmental structure and form no part of the claimed design.

1 Claim, 14 Drawing Sheets
